UNITED STATES PATENT OFFICE.

ORLANDO B. HOLLIS, OF SPOKANE, WASHINGTON.

VEHICLE NUMBER-PLATE.

1,367,659.

Specification of Letters Patent.

Patented Feb. 8, 1921.

Application filed March 25, 1920. Serial No. 368,644.

To all whom it may concern:

Be it known that I, ORLANDO B. HOLLIS, a citizen of the United States of America, residing at Spokane, in the county of Spokane and State of Washington, have invented new and useful Improvements in Vehicle Number-Plates, of which the following is a specification.

This invention pertains to motor driven vehicles number plates and has for its object to provide a permanent frame and inclosure to be rigidly attached to the vehicle and into which the number card is inserted, to be removed and replaced by another card as occasion may require. This will effect a great economy as the frame and inclosure will be permanent and the number card can be of paste-board or other cheap material as the same will be completely protected from the elements.

The details of construction will be hereinafter given and illustrated in the accompanying drawings in which,

Figure 1, is a front elevation of a preferred form of the device carrying a number card.

Fig. 2, is an end elevation of the same.

Fig. 3, is a rear elevation of the same.

Fig. 4, is a front elevation of the same with the parts partially separated.

Fig. 5, is a sectional view taken on the line 5—5 of Fig. 1.

Fig. 6, is a sectional view taken on the line 6—6 of Fig. 1.

Fig. 7, is a front elevation of a modified form of the device carrying a number card.

Fig. 8, is a longitudinal edge view of the same.

Fig. 9, is a broken-away top edge view of the same, with sealing flap folded to place, and

Fig. 10, is an enlarged sectional view taken on the line 10—10 of Fig. 9.

In a detail description of the preferred form shown in Figs. 1 to 6, inclusive, in which like numerals refer to like parts throughout the several views, a frame 11 is channeled as at 12 along the bottom portion and ends, the top portion 13 being merely a flat plate. A back plate 14 has a flange 16 at each end, and a channel 15 at the top.

In assembling, the number card 17 is placed against the inside face of the back plate 14, a transparency 18 placed over the same, and the back plate along with the number card and transparency inserted in

the frame 11, the flange 16 of the back plate 14 engaging the channels 12 at the ends of the frame 11, the bottom edge of the back plate 14 engaging the channel 12 on the bottom portion of the frame 11, and the channel 15 at the top of the back plate 14 engaging the plate 13 of the frame 11, whereby the number card 17 is securely incased as against the elements and behind the transparency 18. Clamping members 19, having transversely arranged portions 20 are then placed over the ends of the assembled parts. The clamping members are curved outwardly to form portions 21, through which openings 22 are provided whereby bolts 23 may be inserted through the openings and the plates secured to the motor vehicle.

Referring now to the modified form shown in Figs. 7 to 10, inclusive, a frame 24 channeled along the top 25, bottom 26 and end 27 is provided with a flap 28 at the end 29, having openings 30 there-through. A fibrous back 31 permanently provided is mounted in the frame 24 with screw bolts 32 permanently set therein. The number card 33 and transparency 34 are then slid into the frame 24 at the unchanneled end 29. The flap 28 is then bent backwardly across the end of the assembled parts and over onto the back of the fiber 31 and fastened by screws 35 inserted through the openings 30 and driven into the fiber 31. Thus the number card is incased against the elements.

The assembled parts may now be secured to the motor vehicle by means of the screw bolts 32. When it is desired to change the number cards, the screws 35 are removed, the flap 28 bent back to the position shown in Fig. 7, the old card removed, the new one placed, and the flap 28 again secured to position by the bolts 35 as hereinbefore described.

What is claimed is:

1. A vehicle number plate comprising a front frame channeled at both ends and at the bottom, a rear solid plate channeled at the top and having a flange at each end, the two parts assembled by the channeled ends of the frame engaging the flanged ends of the back, and channeled bottom of the frame engaging the bottom edge of the back and the channeled top of the back engaging the top of the frame, providing an inclosure protected from the elements.

2. A vehicle number plate comprising a front frame channeled at both ends and at the bottom, a rear solid plate channeled at the top and having a flange at each end, the 5 two parts assembled by the channeled ends of the frame engaging the flanged ends of the back, the channeled bottom of the frame engaging the bottom edge of the back and the channeled top of the back engaging the 10 top of the frame, providing an inclosure

protected from the elements, together with clamping members engaging the edges of the assembled parts and having means for securing the same to the vehicle.

In testimony whereof, I affix my signature 15 in presence of two witnesses.

ORLANDO B. HOLLIS.

Witnesses:

L. L. WESTFALL,
J. C. PARSONS.
